US00D568520S

(12) **United States Design Patent** (10) Patent No.: **US D568,520 S**
Castellucci et al. (45) Date of Patent: ** May 6, 2008

(54) **LIGHTING DEVICE**

(75) Inventors: **Peter C. Castellucci**, Syracuse, NY (US); **Ronald J. Kingston**, Syracuse, NY (US); **Donwoong Kang**, Camillus, NY (US); **Scott W. Osiecki**, Skaneateles, NY (US)

(73) Assignee: **Eveready Battery Company, Inc.**, St. Louis, MO (US)

(**) Term: **14 Years**

(21) Appl. No.: **29/288,019**

(22) Filed: **May 25, 2007**

(51) LOC (8) Cl. **26-05**

(52) U.S. Cl. **D26/65**

(58) Field of Classification Search D26/60-66, D26/93, 107, 118, 128; 362/269, 277, 278, 362/282, 285, 287, 288, 410, 413, 418-430, 362/499

(57) **CLAIM**

We claim the ornamental design for a lighting device, as shown

DESCRIPTION

FIG. 1 is a right top perspective view of the lighting device of the present invention.

FIG. 2 is a right side view of the lighting device of the present invention.

FIG. 3 is a left side view of the lighting device of the present invention.

FIG. 4 is a front view of the lighting device of the present invention.

FIG. 5 is a rear view of the lighting device of the present invention.

FIG. 6 is a top view of the lighting device of the present invention; and,

FIG. 7 is a bottom view of the lighting device of the present invention.

The broken lines shown in the drawings are for the purpose of illustrating portions of the lighting device and form no part of the claimed design.

1 Claim, 5 Drawing Sheets
